CHESTER D. AINSWORTH, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

MULTIBREAK ELECTRIC SWITCH

Application filed September 30, 1929. Serial No. 396,195.

This invention relates to alternating electric switches and circuit interrupters especially adapted to control relatively high potential alternating current circuits.

In my copending application Serial No. 322,730, filed November 30, 1928, I have described a switch having so many serially-connected points of circuit interruption that, for the normal line potential, the potential across any point of interruption cannot exceed the instantaneously-recovered dielectric strength of the circuit-interrupting medium. Thus the alternating current arc cannot be re-established after it has gone out at the end of the first current zero, and the circuit becomes completely opened.

The instantaneously recovered dielectric strength of the medium between a pair of separable contact members, when air is the insulating medium, is around two hundred volts. Consequently, when a switch of this type is designed for use on high voltage circuits the number of sets of separable contact members, or points of circuit interruption that are in series, is considerable. Consequently, the contact resistance between the sum of the contact resistances of the sets of contact members can be considerable, especially when the contact members are not in first class condition, so that it is possible for an arc to be drawn between the main current carrying members of the switch when they separate even though the shunting sets of contact or arcing members are engaged.

One of the main contact carrying members of the switch usually includes a laminated or brush member. It is not advisable to draw an arc from the brush member as the laminations are thin and are liable to be burned by an arc. Consequently, an object of the present invention is the provision of an alternating current switch having separable main current carrying members and a plurality of auxiliary contact members that are connected in series with each other and in shunt with the main current carrying members, combined with other, or tertiary, contact members that normally shunt the auxiliary contact members and thus eliminate their contact resistance especially at the

time the main current carrying members separate.

Due to the fact that the sum of the contact resistances of the auxiliary contact members can be considerable, it is not considered advisable to interpose these contact resistances simultaneously in the switch circuit by the operation of the tertiary set of contact members as an undesired arc can be drawn therebetween. Consequently, it is a further object of the invention to provide the switch with means whereby the sets of auxiliary arcing members are progressively included in series with each other in the opening operation of the switch and preferably also are progressively shunted out of the circuit in the closing operation of the switch.

A further object of the invention is the provision of shunting means for the sets of auxiliary contact members adapted to shunt and also unshunt the auxiliary contact members with a relatively small amount of movement of the main switch operating member so that the switch need not have an unduly large amount of movement in operating.

A further object of the invention is the provision of a high tension switch having a plurality of sets of serially-connected sets of separable contact members and associated mechanism so arranged that a large number of sets of contact members can be installed in a small space.

A further object of the invention is generally to improve the construction and operation of electric switches.

Fig. 1 is a side elevation illustrating more or less diagrammatically the structure of the switch embodying the present invention, the switch being open.

Fig. 2 is similar to Fig. 1, except that the switch is closed.

Fig. 3 is a section taken along line 3—3 of Fig. 1.

As here shown, the switch embodying the present invention includes an insulating frame having horizontal top and bottom bars 10 and 12 and the intermediate vertical connecting bar 14 which also is preferably of insulating material. The frame also has vertical insulating bars 16 and 18 which are lo-

cated on opposite sides of the vertical bar 14 and between the ends of the top and bottom bars.

A series of vertically spaced stationary contact members or blocks 20 are carried in vertically spaced relation by the insulating bars 16 and 18. The uppermost blocks are connected as by circuit conductors 22 separately with the stationary main current carrying members 24 and thus to the alternating current circuit illustrated by the leads 26. Vertical insulating bars 28 are extended between the ends of the top and bottom bars 10 and 12 and are movable horizontally toward and away from each other by appropriate mechanism and are guided for such movement by pins 30 which are carried by said top and bottom bars and are located in horizontal slots 32 in said bars 28. Said bars 28 carry a plurality of movable contact members 34 which are here shown as cylindrical in form and are adapted to be moved between and in contact with the stationary contact members 20 thereby to bridge them. Said contact members 34 and 20 constitute the auxiliary contact members of the switch and are normally in shunt with the stationary main current carrying members 24 when the switch is closed. Said contact members are caused to be engaged and separated by means of upper and lower levers 36 which are pivoted in the middle thereof on pins 38 that are carried by the intermediate vertical bar 14. The ends of said levers are pivotally connected by links 40 to the upper and lower ends of the contact bars 28. Said levers are reciprocated or oscillated between switch open and closed positions by a vertically extended operating rod 42 which is pivoted at 44 to the pivotal junction between said levers and one set of links 40. Thus by lowering said rod 42, the bars 28 are moved inwardly toward each other and are caused to move their contact members 34 into engaging position with the stationary contact members 20. A movement of said rod 42 in the reverse direction effects the separation of the contact members.

In accordance with this invention, means are provided to exclude the contact resistance of the contact members from the auxiliary circuit around the main current carrying members when the switch is closed and to progressively exclude such contact resistance in the closing operation of the switch and to progressively include such contact resistance in the opening movement of the switch. Said means includes the rockers 46 which are composed of conducting material and have serrated or toothed outer faces 48 which rock in engagement with the contact blocks 20, the teeth 48 meshing with the contact blocks.

Mechanism is provided whereby the rockers are tilted from one end of the contact blocks to the other in switch opening and

closing operations of the switch, and also are held in contact with said blocks. Said mechanism includes the set of upper and lower levers 50 which are pivoted on pins 52 that are carried by the intermediate vertical bars 14 between the upper and lower levers 36. Said levers 50 are pivotally connected to links 54 that in turn are pivotally connected respectively to the top and bottom ends of the rockers 46. A vertical operating rod 56 is pivotally connected to the pivotal connections 58 between said levers and links. The levers and links constitute toggles and the arrangement is such that when one toggle is being moved to straighten its members, the other toggle is being moved away from a straight condition. Thus the rockers 46 are caused to rock from one end to the other of the contact blocks 20. The rockers are electrically connected by suitable means as the flexible conductor 60. Consequently, when the rockers are in engagement with the uppermost contact blocks 20, they shunt the lower contact blocks and thereby exclude the contact resistances therebetween from the auxiliary circuit around the main current carrying members of the switch. When the rockers are in engagement with the lowermost contact blocks they serve to connect the two stacks of blocks in series. The rockers thus constitute tertiary contact members that progressively introduce or cut out the auxiliary contact members from the switch circuit.

The operating mechanism for the switch can be of any suitable nature and, as herein shown, includes a horizontally movable operating bar 62 which has a cam groove 64 that engages and raises and lowers the bar 56 for operating the rockers and a second cam groove 66 that engages and operates the bar 42 for operating the auxiliary contact members. The cam grooves 64 and 66 are so arranged that the rod 56 is operated first and is then held stationary while the rod 42 is operated. The rod 56 carries or has movable therewith a bridging member 68 which is adapted to bridge the main current carrying members 24 when the switch is closed and thereby shunt the aforesaid contact members and rockers.

As thus arranged, when the switch is opened, the bridging member 68 is first operated to open the main current path of the switch. The rockers 46 are next operated to introduce the sets of auxiliary contact members in a progressive manner in the switch circuit. The movable auxiliary contact members 34 are then operated to separate them from engagement with the fixed contact members 20 thereby to interpose a large number of points of interruption in series with the circuit. The closing operation of the switch is the reverse of the opening operation. In this manner the contact

resistance of the sets of auxiliary contact members are progressively included in and excluded from the circuit so that arcing at the separable main current carrying members of the switch is prevented both on switch opening and switch closing operations.

5 The supporting frame and its associated parts is relatively narrow as will be seen from an inspection of Fig. 2. Thus, a number of these frames can be placed side by side and connected in series without utilizing an undue amount of space so that a large number of sets of contact members can be arranged in series, thereby to interrupt successfully a high voltage circuit upon the occurrence of the first current zero after all of the contact members have separated.

10 While the invention has been described as incorporated in a switch having so many sets of serially-connected contact members that the potential across the contact members of any one set is kept below approximately two hundred volts, it is apparent that the invention can be incorporated in any switch having a large number of serially-connected points of circuit-interruption, regardless of the potential at each point of circuit-interruption.

I claim:

15 1. An electric switch having a plurality of sets of separable contact members connected in series in the switch circuit, said separable contact members normally engaging each other when the switch is closed, and means to effectively include said contact members in a progressive manner in the switch circuit while said contact members are in engagement prior to the separation of the contact members.

20 2. In an electric switch, the combination of current carrying members, a plurality of sets of separable auxiliary contact members normally shunting said current carrying members, said separable contact members normally engaging each other when the switch is closed, and means to effectively exclude and include said auxiliary contact members progressively from and in said shunting relation while said contact members are in engagement.

25 3. An electric switch having separable main current carrying members, a plurality of sets of separable auxiliary contact members arranged in shunt relation with said main current carrying members, said separable contact members normally engaging each other when the switch is closed, and switch operating mechanism including means to progressively include said auxiliary contact members in effective shunting relation with said main current carrying members while said contact members are in engagement and thereafter to separate said main current carrying members.

30 4. An electric switch having a plurality

of sets of separable contact members adapted to be connected in series in the switch circuit, said separable contact members normally engaging each other when the switch is closed, and switch operating mechanism 70 including means normally excluding said contact members from the switch circuit while said contact members are in engagement, and means to include said contact members in a progressive manner in the 75 switch circuit.

5. An electric switch having a plurality of sets of separable contact members adapted to be connected in series in the switch circuit, said separable contact members normally engaging each other when the switch is closed and switch operating mechanism 80 including means normally excluding said contact members from the switch circuit while said contact members are in engagement, 85 means to include said contact members in a progressive manner in the switch circuit, and means thereafter to separate said contact members.

6. An electric switch including a plurality of sets of separable contact members adapted to be included in series in the switch circuit, said separable contact members normally engaging each other when the switch is closed, means progressively engageable 90 with said contact members to include them progressively in the circuit prior to their separation while said contact members are in engagement, and means thereafter to separate 95 the contact members.

7. An electric switch having a plurality of sets of electric contact members adapted to be connected in series in the switch circuit, said separable contact members normally engaging each other when the switch is closed, connecting means which are movable in a progressive manner to include said contact members progressively in series in the circuit while said contact members are in engagement, and means thereafter to separate 100 said contact members.

8. An electric switch having a plurality of sets of separable contact members adapted to be connected in series in the switch circuit, said separable contact members normally engaging each other when the switch is closed and means to include said contact members progressively in and also to exclude them progressively from the switch circuit including a conducting rocker having means 105 to rock upon said contact members in a progressive manner from one to another while said contact members are in engagement.

9. An electric switch including sets of stationary and movable contact members, the movable contact members being arranged in a straight line, and means to include said contact members in a progressive manner in the switch circuit, including a curved conducting rocker, and means to cause it to rock progress- 110

115

120

sively in engagement with said stationary contact members from one end to the other end of the line.

10. An electric switch having separable main current carrying members, a plurality of sets of separable auxiliary contact members, means establishing an auxiliary circuit around said main current carrying members which excludes at least the major part of said sets of auxiliary contact members, and means to operate the aforesaid means to include said contact members in a progressive manner in the switch circuit and then to separate said main current carrying members and thereafter the auxiliary contact members.

11. An electric switch having a plurality of sets of separable contact members, bridging means which connects them in series in a progressive manner, operating means for said bridging means, and separate operating means for said contact members.

12. An electric switch having a plurality of sets of separable contact members, bridging means which connects them in series in a progressive manner, operating means for said bridging means, separate operating means for said contact members, and operating mechanism for the two aforesaid means including means to operate them in succession.

13. An electric switch including a frame having a pair of vertical insulating members, sets of spaced stationary contact members carried by said vertical members, movable supports carried by said aforesaid frame, sets of movable contact members carried by said movable supports and cooperating with said stationary contact members, operating mechanism to move said movable supports toward and away from each other simultaneously, contact-bridging mechanism including rockers, operating mechanism for said rockers arranged to move them progressively into engagement with said contact members, and means including said rockers connecting said sets of contact members in series.

In testimony whereof, I have signed my name to this specification.

CHESTER D. AINSWORTH.
